CLAIM

I claim the ornamental design for a grillier, as shown and described.

DESCRIPTION

FIG. 1 is a perspective view of a grillier showing my new design;

FIG. 2 is a front view of the grill without the stand;

FIG. 3 is a right side view of the grill without the stand;

FIG. 4 is a top view of the grill without the stand;

FIG. 5 is an enlarged left side view of the grill without the stand;

FIG. 6 is a bottom view of the grill without the stand;

FIG. 7 is an exploded view of the grill without the stand, showing an enlarged detail;

FIG. 8 is a perspective view thereof, showing the grill and stand in a closed position;

FIG. 9 is a front view of the grill in FIG. 8;

FIG. 10 is a top view of the grill in FIG. 8;

FIG. 11 is a side view of the grill in FIG. 8; and,

FIG. 12 is a bottom view of the grill in FIG. 8.

The grill and stand are shown separate in FIGS. 2-12 for clarity of illustration.
